Primary Examiner — Ramzi S Almatrahi*(74) Attorney, Agent, or Firm* — Holtz, Holtz & Volek PC(57) **CLAIM**

The ornamental design for a strobe holding joint for camera, as shown and described.

DESCRIPTION

FIG. 1 is a front, top and left side perspective view of a strobe holding joint for camera showing my new design; FIG. 2 is a rear, bottom and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a top plan view thereof, shown in a condition of use with a camera disclosed in broken lines to illustrate an environment.

The broken lines showing a camera in FIG. 9 represent environmental structure and form no part of the claimed design.
